OZONE GENERATOR

Frank E. Hartman, Chicago, Ill., assignor of one-third to Fred H. Montgomery and one-third to W. Ray Montgomery, both of Chicago, Ill.

Application March 7, 1931, Serial No. 520,892

8 Claims. (Cl. 204—32)

The invention relates generally to ozone generators. More particularly the invention relates to that type of generator which is adapted for use on high frequency electric circuits where high current densities obtain.

One object of the invention is to provide an ozone generator of this type which includes positive means for cooling by liquids the electrodes and the dielectric in order to adapt it for use on high frequency circuits.

Another object of the invention is to provide an ozone generator of the type under consideration which can be readily assembled and dismantled to permit of ready replacement of the parts when necessary.

Other objects of the invention and the various advantages and characteristics of the present generator construction will be apparent from the following detailed description.

The invention consists in the several novel features which are hereinafter set forth and are more particularly defined by the claims at the conclusion hereof.

In the drawings which accompany and form a part of this specification or disclosure and in which like numerals of reference denote corresponding parts throughout the several views: Fig. 1 is an elevation of a generator embodying the invention. Fig. 2 is a vertical section.

Fig. 3 is a plan view of the generator and Fig. 4 is a sectional view taken along line 4—4 of Fig. 2.

The generator which forms the subject matter of the invention comprises an inner tubular electrode 10, a tubular dielectric 11 and an outer electrode 9 secured on the outer periphery of the dielectric. A casing is provided to enclose the dielectric and outer electrode, and comprises a tubular body 12. The lower end of the body 12 is confined in an annular flange 13 on the

top of a hollow head 14 formed of a casting. The upper end of the body 12 is confined in an annular flange 15 depending from a hollow head 16. A cap 17 fits over and closes the open top of the head 16. A series of tie-bolts 18 extend through

lugs 19 on the cap 17, lugs 16a on head 16, and lugs 20 projecting from the lower head 14, and serve removably to clamp together both heads, the casing-body and the cap. The lower end of the body 12 is seated on a packing ring 21 which

rests on an annular shoulder or wall 22 integrally formed with the head 14. An annular shoulder or wall 23, integral with the casing 16, is clamped against the upper edge of the body 12. A packing gasket 24 is interposed between the cap 17 and the upper head 16. The tie bolts 18 clamp the upper

and lower heads to the body to form air-tight chambers in the heads respectively.

The lower end of the inner electrode has a tubular extension 10a of reduced diameter and is secured in a sleeve 26 of porcelain or other insulating material to insulate the inner electrode from the lower head 14. The tubular portion 10a of the inner electrode has an annular shoulder 26a fitting in a socket 27 in the upper end of the porcelain sleeve 26. A filling of suitable cement 28 in

the socket 27 above shoulder 26a and around the tubular portion 10a of the inner electrode secures the insulating sleeve to the electrode so they will be removable and replaceable as a unit. The insulating sleeve 26 is formed with an annular shoul-

der 27b which seats on the lower wall of the head 14. This sleeve and the inner electrode supported thereby are supported wholly from the lower head 14. The upper end of the inner electrode has a constricted portion 10b and is closed to form a

chamber through which cooling liquid will flow. The sleeve 26, with the inner electrode, is secured in the head 14 against upward displacement by a split ring 29 held in a peripheral groove in the sleeve and having its outer portion projecting suffi-

ciently to engage and lap the lower wall of the head 14. A packing box, comprising packing 30 around ring 29 and a gland 31 which is screw-threaded to a downwardly projecting nipple on the head 14, forms a fluid-tight connection be-

tween the sleeve 26 and the head 14.

The tubular dielectric 11 is cylindrical or straight, and passes through and fits in the lower wall 23 of head 16 and the upper wall 22 of head 14. Both ends of the dielectric are open to permit air to flow therethrough and around the inner electrode 10.

The upper end of the dielectric has a flared annular shoulder to position centrally and support the dielectric in the casing. The outer periphery of the inner electrode is spaced from the inner periphery of the dielectric, as well understood in the art.

An air pipe 32 is connected to the side wall of head 16 to deliver air into a vertical duct 33 formed in said head. The lower end of duct 33 is closed and its upper end communicates with a cross-duct 34 which is formed in the cap 19, and terminates in a central downwardly extending opening 35.

A tube or nipple 36 of porcelain insulating material is secured in opening 39 in cap 19, and extends downwardly from said duct 35 to discharge air centrally into the dielectric and above the inner electrode. This tube 36 provides for maximum insulation at the inlet end of the dielectric. An air outlet pipe 37 for air

is connected to the side wall of the lower head 14.

Provision is made for circulating the cooling liquid through the inner electrode. For this purpose a hollow coupling 38 is secured to the 5 lower end of the tubular extension 10a of the inner electrode which projects below the insulating sleeve 26. An inlet pipe 39 for the cooling liquid is screw-threaded to one side of said coupling. An outlet pipe 40 has its lower end screw-threaded into the lower wall of coupling 38 and extends upwardly to a point adjacent the top of the inner electrode, so that the liquid will flow 10 from the upper portion of the electrode downwardly through pipe 40. The space between pipe 15 40 and the inner periphery of portion 10a of the inner electrode forms a chamber through which the cooling liquid will flow upwardly from coupling 38 to cool the inner electrode. A discharge pipe 41 is connected to the coupling 38 to carry 20 off the liquid from pipe 40.

The invention also provides means for circulating cooling liquid around the tubular casing 12 to cool the outer electrode and the dielectric. This means comprises a jacket composed of a tube or 25 body 42 provided at each of its ends with a ring 43 which is welded to said tube. Each ring 43 fits around the body 12, and is provided with a channel containing packing 44. A packing gland or ring 45 is secured to each ring 43 by screws 30 46 to cause the packings to form a liquid-tight joint between the jacket and the casing 12. These packings clamp the jacket to casing-body 12. This makes it possible easily to assemble 35 the jacket around the casing 12, to remove it when desired and to slide the jacket along the body 12 to the desired position. A pipe 47 is connected to the lower ring and serves to deliver cooling liquid into the jacket. An outlet pipe 48 for the cooling liquid is connected to the upper 40 ring 43. A vertical corrugated copper sleeve 12d is interposed between casing 12 and the outer electrode on the dielectric to conduct heat to the casing which is cooled by the liquid flowing through the jacket.

45. The cooling liquid consists preferably of a suitable oil which is forced by a pump 49 through a pipe 50 to the inlet pipe 47 of the jacket around body 12, and also to the inlet pipe 39 which delivers oil to the inner electrode 10. The connection between pipe 39 and pipe 50 comprises a glass 50 tube 51 which serves to insulate the pipe 39 from the pipe 47 which is connected to the jacket around casing 12 to prevent current from passing from the body 12 to the inner electrode. The liquid discharged from the jacket around body 12 through pipe 48 and from the inner electrode through pipe 41, is conducted by a pipe 52 to a closed expansion tank 53. The connection between pipe 41 and pipe 52 comprises an insulating tube 54 of glass to prevent current from passing from the inner electrode to the jacket around body 12. In practice, it has been found that oil is hygroscopic, and it is desirable to retain the oil in a closed circuit to prevent the 60 accumulation of moisture therein. For this purpose the oil from the generator is delivered into the closed expansion tank and the circulating lines are closed. This tank is provided with an air cock 54a to permit the air displaced by the oil to escape when originally filling the system. A suitable heat exchanger or cooler 55 is provided around a coil 57 of the line between the expansion tank and the inlet of the pump 49 to cool the oil before it has returned to the generator. Water is circulated through the cooler 55.

A pipe 56 delivers oil from tank 53 into the coil 57 in the heat exchanger, and a pipe 55a delivers the cooled oil from said coil to the inlet side of the pump.

The generator casing is composed of parts 5 which can be readily assembled and secured together by means of the tie-bolts 18. The inner electrode is removably and concentrically sustained by the lower head 14 of the casing. The dielectric which consists of a straight glass tube 10 can be inserted into the casing before the cap 17 is secured in place. The jacket around the body 12, which consists of a straight tube, can be slipped over the tube before it is assembled with the heads.

One of the conductors of a high frequency electric circuit is connected to any suitable part of the casing which is in electrical contact with the outer electrode on the dielectric, and the other conductor is connected to the coupling 38 on the 20 lower end of the inner electrode which is insulated from the main casing by sleeve 26 to produce a discharge across the gap between the dielectric and the inner electrode. The air passes through the dielectric tube and around 25 the inner electrode, as well understood in the art. The pump 49 delivers oil from the tank 53 through pipe 47 into the jacket around the tubular casing, and also delivers oil under pressure through pipe 39 to the coupling 38. The distribution of 30 the oil from the pump, so it will pass in proper proportions through the outer jacket and through the inner electrode may be controlled by the size of the orifice in the delivery end of pipe 41. The oil circulating around the body 12 cools it, and 35 carries off the heat generated in the dielectric and outer electrode which passes through the corrugated copper conductor 12d. The oil flowing upwardly through the inner electrode flows out through the pipe 40 and thence through pipe 41. The oil from pipes 48 and 41 are discharged into 40 the tank 53 for recirculation. The heat exchanger 55 cools the oil, so that it can be recirculated. This exemplifies a cooling system for the inner and outer electrodes, in which the cooling liquid is 45 circulated in a completely closed circuit, so that no moisture in the atmosphere will be absorbed by the oil. The air space in the upper portion of the expansion tank permits the oil to expand or contract.

The invention exemplifies an ozone generator with a closed system for circulating oil to cool the inner and outer electrodes; it also exemplifies an ozone generator which is composed of parts 50 which can be manufactured at a low cost and which can be readily assembled and dismantled where repair or replacement of any of the parts becomes necessary.

The invention is not to be understood as restricted to the details set forth, since these may 60 be modified within the scope of the appended claims, without departing from the spirit and scope of the invention.

Having thus described the invention, what I claim as new and desire to secure by Letters Patent, is:

1. In an ozone generator, the combination of a tubular casing comprising a tubular body, hollow heads at the ends of said body, a removable cap for closing one of said heads, tie-bolts extending 70 between the cap and the other head for conjointly and releasably clamping the body, heads, and cap together, tubular electrodes in the body, and a tubular dielectric associated with said electrodes.

2. In an ozone generator, the combination of a tubular casing comprising a tubular body, hollow heads at the ends of said body, a removable cap for closing one of said heads, means for releasably clamping the body, heads, and cap together, tubular electrodes in the body, a tubular dielectric associated with the electrode and arranged so as to form with one of the electrodes a tubular ozone-forming space in communication with the hollow heads, an air inlet and an outlet connection for the heads, the cap being provided with a duct communicating with the inlet connection in one of the heads and delivering air centrally into the casing.
- 15 3. In an ozone generator, the combination of a casing comprising a tubular body, tubular electrodes in the body, a tubular dielectric associated with the electrodes, and a jacket for cooling liquid, extending around said body and comprising a tubular member and packing boxes at the ends thereof, said member being slidable along the casing-body and secured in position on the body by said boxes.
- 20 4. In an ozone generator, the combination of a casing comprising a tubular body, tubular electrodes in the body, a tubular dielectric associated with the electrodes, and a jacket for cooling fluid around said body, comprising a tubular member and packing boxes at the ends thereof, said member being movable along the casing-body together with the boxes and being secured in position solely by said packing boxes.
- 25 5. In an ozone generator the combination of a casing comprising a tubular body, a tubular dielectric within the body, tubular electrodes on opposite sides of the dielectric, an insulating sleeve secured in one end of the casing, the inner electrode having one of its ends closed and its other provided with a tubular extension extending through and secured in said sleeve, a tube for cooling fluid extending through said extension and
- 30 having the inner end thereof terminating adjacent the closed end of the inner electrode, a coupling member secured to the outer end of said extension and abutting against one end of the sleeve so as to hold the extension against longitudinal displacement in one direction with respect to the sleeve, and means connected to the coupling member for delivering cooling fluid thereto for circulation through the inner electrode and discharge via the tube.
- 35 6. In an ozone generator, the combination of a casing comprising a tubular body, a tubular dielectric within the body, tubular electrodes on opposite sides of the dielectric, an insulating sleeve in which one of the electrodes is secured, extending through one end-part of the casing, and a split ring for securing the sleeve in the casing extending around the sleeve and coacting with said end-part of the casing.
- 40 7. In an ozone generator, the combination of a casing comprising a tubular body, a tubular dielectric within the body, tubular electrodes on opposite sides of the dielectric, an insulating sleeve in which the inner electrode is secured, extending through one end-part of the casing, a split ring for securing the sleeve in the casing and a packing box around said ring and sleeve.
7. In an ozone generator, the combination of a casing comprising a tubular body, a tubular dielectric within the body, tubular electrodes on opposite sides of the dielectric, an insulating sleeve in which the inner electrode is secured, extending through one end-part of the casing, a split ring for securing the sleeve in the casing and a packing box around said ring and sleeve.
- 30 8. In an ozone generator, the combination of a tubular casing, a tubular dielectric in the casing, a tubular outer electrode around the dielectric, a tubular inner electrode closed at one of its ends and arranged within the dielectric so as to form therebetween an ozone-forming space, a connection for delivering air into said space comprising a tube of insulating material separate from the dielectric and centrally disposed and supported in the casing and having an open end spaced from the closed end of the inner electrode but arranged to deliver air thereagainst and into the aforesaid space.
